SPINDLE MOUNTING

Albert E. Winslow, New London, Conn., assignor,
by mesne assignments, to Atwood Machine
Company, Stonington, Conn., a corporation of
Connecticut

Application May 11, 1940, Serial No. 334,664

6 Claims. (Cl. 57—89)

This invention relates to a mounting for a spindle or the like, a plurality of which units are to be driven from a single belt traveling about the machine; and has for one of its objects to resiliently urge the whorl against the belt.

Another object of the invention is to provide an eccentric mounting of the spindle with a spring causing movement of the eccentric mounting to change the position of the spindle with reference to the driving belt.

Another object of the invention is to provide a unit, the moving parts of which may operate in a lubricant at all times so that the moving parts may be easily operated.

With these and other objects in view, the invention consists of certain novel features of construction, as will be more fully described, and particularly pointed out in the appended claims.

In the accompanying drawing:

Fig. 1 is a sectional view of the spindle mounting secured to the framework of the machine and illustrating in section the belt for driving the same;

Fig. 2 is a section on line 2—2 of Fig. 1;

Fig. 3 is a sectional view taken on substantially line 3—3 of Fig. 1;

Fig. 4 is a fragmental, sectional view on line 4—4 of Fig. 1;

Fig. 5 is a sectional view looking on substantially line 5—5 of Fig. 3.

In spinning or twisting machines in which a single traveling belt is utilized for driving a plurality of spindles, the spindle is resiliently urged to cause its whorl to contact with the traveling belt for actuation of the blade; and in order that the moving parts may be well lubricated, I have arranged to provide a cup or casing for containing a lubricant and have mounted the moving part holding the spindle in this lubricant and

provided a resilient element which urges the moving part with the spindle resiliently into engagement with the belt to actuate the whorl on the blade; and in some instances, when it is necessary to hold the spindle out of contact with the belt, a catch may be utilized for this purpose; and the following is a more detailed description of the present embodiment of this invention, illustrating the preferred means by which these advantageous results may be accomplished:

With reference to the drawing, 10 designates the frame of a spinning or twisting machine, and 11, the belt which travels the length of the machine for operating a plurality of spindles; the body of the mounting is designated 12 and consists of a cup-shaped casing having a hollow in-

terior 13. A bolt 14 will serve to bind the frame between the jaw 15 and the casing 12 to hold the body, securely mounting it in position. An adjustment with reference to the frame may be had by the set screw 16.

Within this hollow 13 of the casing I have centrally pivoted a member 17 having circular portions 18 and 19 adjacent its upper and lower ends to fit and having a bearing in the cylindrical interior of the casing 12. This member has a 10 conical support 20 in step 21 in the bottom wall of the casing. The member is reduced between these circular end portions and is provided with a bore 22 located eccentrically with reference to the center axis of this member 17. In this bore 15 22 I have mounted a spindle, designated generally 23, which has a base 24 engaging the upper surface of the member 17.

This spindle is of any conventional form provided with a blade 25, a whorl thereon 26, and a 20 step 27 to prevent lifting of the whorl. A spring 28 serves to resiliently mount this spindle casing in position on the member 17. Extending outwardly from the recessed portion 29 of the member 17 there is an abutment fin 30 against which 25 a plunger 31 acts. This plunger is guided in a bore 32 formed through the wall of the casing and into the extension 33 from the casing. A spring 34 serves to force the plunger inwardly against the abutment 30. This spring may be 30 adjusted as to tension by the threaded plug 35 held in position by the check-nut 36.

The upper cylindrical portion 18 of the member 17 is notched as at 37 and a latch 38 which is forced inwardly by spring 39 and retractable 35 by handle 40 will engage this notch to prevent rotation of the member 17 by action of the spring 39. This notch is so located that in normal operation the latch will not engage the same, the engagement occurring only when the member 17 is 40 rotated through a substantial arc.

In use, the bracket is mounted upon the frame 10 and the bracket will be so positioned that when the parts are in substantially the relationship shown in Fig. 3, the whorl will engage the 45 belt 11 with substantially the desired amount of pressure, it being understood that the spring 34 tends to rotate the member 17 and the spindle carried thereby into engagement with the belt by reason of the action of the spring 34. This 50 spring will allow any irregularities in the belt, such as a connection at the ends, to swing the spindle against the action of the spring while causing the spindle to always follow the belt and engage the same with sufficient tension to ob-

tain the desired traction necessary for driving the spindle.

The foregoing description is directed solely towards the construction illustrated, but I desire 5 it to be understood that I reserve the privilege of resorting to all the mechanical changes to which the device is susceptible.

I claim:

1. A spindle mounting comprising a cup-shaped 10 body to be fixed to a portion of the frame, a member in said body mounted to move about a central axis, means for eccentrically mounting a spindle on said member, resilient means for urging movement of said member to vary the position of the spindle with reference to said body.

2. A spindle mounting comprising a cup-shaped 15 body to be fixed to a portion of the frame, a member in said body mounted to move about a central axis, means for eccentrically mounting a spindle on said member, resilient means for urging movement of said member to vary the position of the spindle with reference to said body, and a fluid lubricant in said body.

3. A spindle mounting comprising a cup-shaped 20 body to be fixed to a portion of the frame, a cylindrical member rotatably mounted within said body provided with a radial abutment, means for eccentrically mounting a spindle on said member, resilient means engaging said abutment for urging movement of said member and the spindle 25 whorl against a driving belt of a machine in which the same is positioned.

4. A spindle mounting comprising a body to be fixed to a portion of the frame and having an

opening therein, a member mounted in said opening to move about an axis centrally disposed with respect to the member, means for eccentrically mounting a spindle on said member, and means tending to cause movement of said member about said axis to vary the position of said spindle with reference to said body portion. 5

5. A spindle mounting comprising a body to be fixed to a portion of the frame and having an opening therein, a member mounted in said opening to move about an axis centrally disposed with respect to the member and provided with an abutment thereon, means for eccentrically mounting a spindle on said member, resilient means tending to cause movement of said member to vary 15 the position of said spindle with reference to said body portion, and a spring moved latch on said body engageable by said abutment to limit the movement of said support.

6. A spindle mounting comprising a body to be 20 fixed to a portion of the frame, a member having an opening therein, means for mounting said member to rotate about a central axis with reference to said body, means for eccentrically mounting a spindle on said member, resilient means for 25 urging movement of said member to vary the position of the spindle with reference to said body, and a spring-urged latch positioned on said body and having a portion arranged to enter into said opening upon a predetermined movement of 30 said member to lock the same against action by said resilient means.

ALBERT E. WINSLOW.
